UNITED STATES PATENT OFFICE.

MATTIE H. EVELETH, OF BOSTON, MASSACHUSETTS.

DESIGN FOR A GAME-BOARD.

SPECIFICATION forming part of Design No. 31,815, dated November 7, 1899.

Application filed October 16, 1899. Serial No. 733,834. Term of patent 7 years.

To all whom it may concern:

Be it known that I, MATTIE H. EVELETH, a citizen of the United States, residing at Boston, in the county of Suffolk and State of Massachusetts, have invented and produced a new and original Design for a Game-Board, of which the following is a specification, reference being had to the accompanying drawings, forming a part thereof.

10 In the drawings, Figure 1 shows a plan view of a game-board embodying my design, and Fig. 2 shows a cross-section of the same.

My design consists in the rectangular field traversed at regular intervals by parallel lines 15 A, intersected at right angles by a similar series of parallel lines A', constituting sixty-

eight squares within the field, arranged as shown, there appearing fourteen darkened or shaded squares upon each of two opposite sides of said field.

The leading feature of my design consists in the rectangular field traversed by two series of regular parallel lines intersecting at right angles with shaded squares on two opposite sides of the field, as shown.
